CLAIM

The ornamental design for an air freshener device, as shown and described.

DESCRIPTION

FIG. 1 is a front perspective view of the air freshener device in accordance with my new design;

FIG. 2 is a left side elevational view thereof, the opposite side being substantially identical except for the position of the apertures;

FIG. 3 is a rear side elevational view thereof;

FIG. 4 is a top plan view thereof; and,

FIG. 5 is a bottom plan view thereof.
